UNITED STATES PATENT OFFICE.

JOSHUA B. BARNES, OF SPRINGFIELD, ILLINOIS.

DESIGN FOR A WRENCH FOR STAY-BOLTS FOR BOILER-SHEETS.

SPECIFICATION forming part of Design No. 34,837, dated July 23, 1901.

Application filed June 8, 1901. Serial No. 63,802. Term of patent 14 years.

To all whom it may concern:

Be it known that I, JOSHUA B. BARNES, a citizen of the United States, residing at Springfield, Illinois, have invented and produced a new and original Design for a Wrench for Stay-Bolts of Boiler-Sheets, of which the following is a full, clear, and exact specification.

In the accompanying drawings, Figure 1 is an elevation of the wrench, showing it from one side. Fig. 2 is a like view showing the wrench a quarter-turn from the position of Fig. 1. Fig. 3 shows the wrench in end elevation, while Fig. 4 is an elevation of the opposite end.

The leading feature of the invention resides in the general shape and configuration of the device. As shown, the extreme end is threaded at *a*, and immediately in rear of the threaded portion is a projecting shoulder *b*, formed

by enlarging the body *c* of the tool, this body *20* portion being substantially cylindrical and of uniform diameter except where it enlarges at the point *b*. There is a further enlargement *d*, and through this enlargement, as shown in Fig. 2, there is an opening *e*. There *25* is a third enlargement *f*, and through this enlargement extends an opening *g* at right angles to the opening *e*. From the enlargement *f* to the end of the tool the body portion *c* is substantially cylindrical. *30*

What I claim is—

The design for a wrench as herein shown and described.

JOSHUA B. BARNES.
